(57) **CLAIM**

The ornamental design for a telescopic gate fence, as shown and described.

DESCRIPTION

FIG. 1 is a first perspective view of a telescopic gate fence showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 i is a perspective view of another state of the telescopic gate fence thereof;

FIG. 10 is an enlarged view of the selected portion in FIG. 1;

FIG. 11 is an enlarged view of the selected portion in FIG. 1;

FIG. 12 is an enlarged view of the selected portion in FIG. 2;

FIG. 13 is an enlarged view of the selected portion in FIG. 2; and,

FIG. 14 is an enlarged view of the selected portion in FIG. 2.

The broken lines shown in the drawings depict portions of the telescopic gate fence in which the design is embodied that form no part of the claimed design. The dot-dash broken line circles depict the limits of the enlarged views and form no part of the claimed design.
